UNITED STATES PATENT OFFICE

167,457

INDOOR ANTENNA FOR TELEVISION

Robert Allan Gordon, Fairfield, Ala.

Application June 14, 1952, Serial No. 20,207

Term of patent 14 years

(Cl. D26—14)

To all whom it may concern:

Be it known that I, Robert Allan Gordon, residing at Fairfield, in the county of Jefferson and State of Alabama, have invented a new, original, and ornamental Design for Indoor Antenna for Television, of which the following is a specification, reference being had to the accompanying drawing, forming part thereof, in which Fig. 1 is a top plan view; and Fig. 2 is a side elevational view of the indoor antenna for television, showing my new design.

I claim:

The ornamental design for an indoor antenna for television, as shown.

ROBERT A. GORDON.
